UNITED STATES PATENT OFFICE

LAWRENCE G. SHOOK, OF LOS ANGELES, CALIFORNIA

VENETIAN BLIND FOR MOTOR VEHICLES

Application filed October 1, 1927. Serial No. 223,333.

This invention relates to improvements in blinds, and particularly to what are commonly called Venetian blinds. The invention may be considered as an improvement over my pending application for a blind, Serial No. 120,101, filed July 2, 1926.

An object of this invention is to provide an improved Venetian blind construction which is primarily designed to be used upon vehicles of the closed car type wherein there is a window frame either on a door of the vehicle or on the body, in which is slidable, a window. In vehicles of the closed car type, there is a window frame in which is movable a window adapted to occupy a position across the window opening in the frame, or a concealed position in a window receiving pocket therebelow.

Another object of the invention is to provide a Venetian blind which is also slidable in the window frame so as to occupy a position across the window opening or a concealed position in the window receiving pocket.

Another object of the invention is to provide a blind construction which is so designed as to occupy a small amount of space, that is, that the blind is of minimum thickness so that the window frame will not be required to be widened materially so as to receive both the window and the blind.

A further object of the invention is to provide a blind construction consisting of a window frame in which is slidable a blind frame carrying a blind, and to provide means for automatically tilting the slats of the blind when the blind frame is moved into a position over the window opening in the frame.

Other objects of the invention are to provide a Venetian blind of improved construction having a novel means for actuating the slats so as to tilt them about their longitudinal axes, and to provide a blind wherein the slats are held against rattling.

With the foregoing and other objects in view which will be made manifest in the following detailed description and specifically pointed out in the appended claims, reference is had to the accompanying drawings for an

illustrative embodiment of the invention, wherein:

Figure 1 is a sectional view of the improved blind taken substantially upon the line 1—1 upon Figure 2, parts being shown 55 in elevation.

Fig. 2 is a sectional view taken upon the line 2—2 upon Figure 1, illustrating the blind in a position just below its uppermost 60 position.

Fig. 3 is a view similar to Figure 2, illustrating the blind in position slightly below that shown in Figure 2.

Fig. 4 is a view similar to Figure 2, showing the blind in position slightly below that 65 shown in Figure 3.

Fig. 5 is a view similar to Figure 2, the blind being shown in its lowermost position.

Fig. 6 is a view taken on the line 2—2 upon Figure 1, the blind being shown as having 70 been removed to illustrate a detail of construction upon the window frame.

Fig. 7 is a view in elevation, parts being broken away and other parts being shown in section, illustrating the details of construction of the improved blind. 75

Fig. 8 is a sectional view taken upon the line 8—8 upon Figure 7.

Fig. 9 is an end view in elevation, taken in the direction of the arrow 9 upon Figure 7. 80

Referring to the accompanying drawings wherein similar reference characters designate similar parts throughout, the invention is illustrated as having been applied to a door of an automobile of the closed car type. The door provides a window frame having a top 10, bottom 11 and sides 12 and 13. The side walls 14 and 15 connect the lower ends of the sides 12 and 13 to the bottom 11, forming a window receiving pocket 16 below the window opening generally designated at 17. The sides 12 and 13 above the side walls 14 and 15 and the top 10, are preferably provided with inwardly extending flanges indicated at 18. Slidable within the window frame thus provided, is a window 19 adapted to assume a position either within the window receiving pocket 16 or across the window opening 17. This window can be raised and lowered in any preferred manner, such as by a handle 100

20 located upon the interior of the door and indicated by dotted lines on Figure 1, Figure 1 being a view from the outside of the door.

The improved blind consists of a blind frame preferably formed of metal and rectangular in form, having a top 21, sides 22 and 23 and a bottom 24. This blind frame is slidable in the window frame in a plane parallel to the window 19, and is capable of 10 assuming a position across the window opening 17 or within the window receiving pocket 16. The blind frame can be raised and lowered by any preferred construction such as that which is generally used for raising and 15 lowering the window 19. This may be accomplished by rotating the crank or handle 25 which is also preferably located on the inside of the door adjacent the handle or crank 20. A plurality of parallel slats 26 20 extend across the blind frame between its sides 22 and 23. These slats may be formed of any desirable material such as thin strips of wood. Each slat 26 has a pin 27 secured thereto at one end of its ends near one of its 25 longitudinal side edges. The pins 27 extend into apertures 28 formed in the side 23 so as to pivotally connect the mentioned ends of the slats to the side 23. On the opposite ends of the slats near the mentioned longitudinal 30 side edge, there are mounted pins 29 which have shoulders 30 bearing against the ends of the slats. The pins 29 extend through washers 31 into apertures 32 formed in the side 22, thus pivoting these ends of the slats 35 to the sides 22. Coil springs 33 are compressed about the pins 29 between the washers 31 and the shoulders 30, urging the slats toward the side 23 of the frame to prevent rattling. Between the ends of the slats 26 40 which carry the pivot pins 27 and the side of the blind frame 23, there is arranged an actuating bar 34 which is pivotally connected to the end of each slat by pivot pins 35. Notches 36 are formed in the actuating bar 34 which 45 accommodates the pivot pins 27 when the bar 34 is in position wholly within the blind frame. It will be understood that by pulling the actuating bar 34 downwardly from the position shown in Figure 7, that the slats 26 50 are simultaneously tilted about the longitudinal axes which are arranged adjacent one longitudinal side edge of each slat. When the slats first start to tilt, the actuating bar will be carried thereby and caused to move 55 outwardly from within the blind frame. A continued movement of the actuating bar causes the slats to move from the position shown in Figure 4 to the position shown in Figure 3, and further movement moves them 60 into the position shown in Figure 2. It is possible by pulling the actuating bar further downward to cause the slats to assume positions wherein all slats are extending downwardly from their axes of rotation, and 65 are arranged parallel to the window 19, and

in such position the actuating bar 34 again assumes a position wholly within the blind frame. On the lower end of the actuating bar there is a pin 36 which extends through a notch 37 in the side 23 so that the end of the pin projects laterally beyond the side 23. A second notch 37' is arranged below the first notch to accommodate the pin 36 when the actuating bar is in its lowermost position. On the interior of the window frame there is formed a groove 38 into which the pin 36 extends. The major portion of this groove is straight as clearly indicated upon Figure 6, but the upper end is bent outwardly as at 39, and then inwardly as at 40.

The operation of the improved blind is as follows:

When the blind frame is in its lowermost position as shown in Figure 5, the top of the blind frame is approximately flush with the flanges 41 which are preferably provided on the top of the side walls 14 and 15. The top of the blind frame thus fills the gap between the flanges and the window 19 to prevent rain or snow from falling between the side wall 15 and the window, it being understood that the improved blind is preferably arranged on the outside of the window. By rotating the crank 25 the blind frame will be lifted. When the blind frame is in its lowermost position, all of the slats are extending upwardly from their longitudinal axes of rotation and are wholly within the blind frame and parallel to the window 19. During the major portion of the upward movement of the blind frame, the slats remain in this position, but on approaching the uppermost position of the blind frame, the pin 36 enters the outwardly extending portion 39 of the groove 38. This causes a pull to be exerted on the actuating bar and moves the lower end of the actuating bar outwardly, causing the slats to move from their vertical positions into inclined positions as shown in Figure 4. By moving the blind frame upwardly a short distance farther, the pin 36 will be located at that point in the groove 38 where the portions 39 and 40 join each other. In such position the slats will assume horizontal positions as shown in Figure 3. By moving the blind frame further upwardly, the pin 36 enters the portion 40 of the groove 38 causing the slats to assume the position shown in Figure 2. When the pin is in the uppermost end of the groove portion 40, the top of the blind frame is engaging the top 19 of the window frame and the actuating bar is in its lowermost position wherein the slats are all again vertical but extending downwardly from their longitudinal axes of rotation. By lowering the blind frame by the crank 25, the operations as above described and their sequence are reversed, so that on lowering the blind frame the slats will first be caused to swing into the 130

vertical position and then to be lowered bodily within the window receiving pocket 16.

From the above described construction it will be appreciated that a novel Venetian blind is provided which may be advantageously employed upon vehicles of the closed car type because of the minimum thickness occupied by the blind when in its collapsed position. It will be readily understood that although the blind has been primarily designed to be used upon vehicles, that it is not limited to such use but may be used in other structures and for analogous purposes.

It will be noted that by virtue of the fact that each slat is pivoted for rotation about a longitudinal axis near one of its side edges, that the other side edge of each slat will swing through an arc more remote from the window than the first side edges. In this way, it is possible to have the blind frame very close to the window 19, which could not be accomplished if the slats were pivoted for rotation about longitudinal axes arranged in the centers of the slats.

Various changes in the details of construction may be made without departing from the spirit or scope of the invention as defined by the appended claims.

I claim:

1. In combination with a vehicle having a window opening and a window adapted to occupy the window opening or a concealed position therebelow, means providing a Venetian blind adapted to occupy the window opening or a concealed position therebelow adjacent the window when the window is in concealed position, and means operable upon shifting the blind from one position to another for causing the slats of the blind to be turned.

2. In combination, a window frame, a Venetian blind frame movable therein, and slats extending across the Venetian blind frame forming a Venetian blind therein, said slats being tilttable in the Venetian blind frame, and means for tilting the slats, said means being operable by moving the Venetian blind frame relatively to the window frame.

3. In combination, a window frame having a window receiving pocket arranged adjacent the window opening, a window movable in the window frame adapted to occupy the window opening or a position in the pocket, and a plurality of slats extending across the window frame constituting a Venetian blind, said slats being movable to occupy a position across the window opening or a position in the pocket, and means for causing the slats to occupy positions parallel to the window when the slats are disposed within the pocket.

4. In combination, a window frame having a window receiving pocket arranged adjacent the window opening therein, a window movable in the window frame adapted to occupy

a position over the window opening or in the pocket, a blind frame movable in the window frame adapted to occupy a position over the window opening or in the pocket, a plurality of parallel slats pivotally mounted upon the blind frame, and an actuating bar pivotally connected to each of said slats whereby when the blind frame is across the window opening the slats may be tilted thereby, said actuating bar having a part engageable with the window frame whereby upon moving the blind frame over the window opening the slats will be automatically tilted by said bar.

5. In combination, a window frame having a window receiving pocket arranged adjacent the window opening therein, a window movable in the window frame adapted to occupy a position over the window opening or in the pocket, a blind frame movable in the window frame adapted to occupy a position over the window opening or in the pocket, a plurality of parallel slats pivotally mounted upon the blind frame, and an actuating bar pivotally connected to each of said slats whereby when the blind frame is across the window opening the slats may be tilted thereby, said actuating bar carrying a pin slidable in a groove in the window frame whereby upon moving the blind frame into a position over the window opening the slats will be caused to be tilted thereby.

6. A Venetian blind comprising a blind frame, guide means for the blind frame, means providing a Venetian blind in the blind frame, and means for automatically causing the slats in the blind to be tilted on moving the blind frame in either direction, and means for moving the blind frame.

7. A Venetian blind comprising a blind frame, guide means for the blind frame, means providing a Venetian blind in the blind frame, and means for causing the slats of the blind to remain stationary during certain parts of the movement of the blind frame and causing the slats to tilt during other parts of the movement of the blind frame.

8. A Venetian blind comprising a blind frame, guide means for the blind frame, means providing a Venetian blind in the blind frame, means for causing the slats of the blind to remain stationary during certain parts of the movement of the blind frame and causing the slats to tilt during other parts of the movement of the blind frame, and means for moving the blind frame.

9. In combination, means providing a window opening and a pocket adjacent the window opening, a window receivable in the pocket adapted to be positioned over the window opening, a blind frame receivable in the pocket adapted to be positioned over the window opening, means providing a blind in the blind frame, and means for moving the window into the pocket or over the opening,

and unitary means for moving the blind frame into the pocket or over the opening.

10. A Venetian blind comprising a blind frame, guide means for the blind frame, means providing a Venetian blind in the blind frame, actuating means for tilting the slats of the blind, said actuating means being operatively connected to the guide means so as to control the movements of the slats while the blind frame is being moved in the guide means.

11. A Venetian blind comprising means providing a window opening, a movable blind frame movable across the opening, a plurality of slats tiltably mounted in the blind frame, and means for causing the slats to be automatically tilted with respect to the blind frame as the blind frame moves across the opening.

12. A Venetian blind comprising means providing a window opening, a movable blind frame movable across the opening, a plurality of slats tiltably mounted in the blind frame, and means for causing the slats to be automatically tilted with respect to the blind frame as the blind frame approaches its window opening occupying position.

13. A Venetian blind comprising means providing a window opening, a movable blind frame movable across the opening, a plurality of slats tiltably mounted in the blind frame, means for causing the slats to be automatically tilted with respect to the blind frame as the blind frame moves across the opening, and means for moving the blind frame.

14. A Venetian blind comprising means providing a window opening, a movable blind frame movable across the opening, a plurality of slats tiltably mounted in the blind frame, means for causing the slats to be automatically tilted with respect to the blind frame as the blind frame approaches its window opening occupying position, and means for moving the blind frame.

In testimony whereof I have signed my name to this specification.

LAWRENCE G. SHOOK.
